LIFESAVER DEVICE

Edwin H. Burkhardt, Minneapolis, Minn.

Application July 28, 1949, Serial No. 107,189

8 Claims. (Cl. 9—19)

1

This invention relates to a life-saving device, and particularly to a life-saving device comprising an inflatable member and automatically acting means for inflating said member.

It is an object of this invention to provide a life-saving device comprising an inflatable member, a vessel containing air or other gas under pressure, and means acting automatically when the device is submerged for discharging the air or gas from said vessel into said inflatable member.

It is a further object of the invention to provide a life-saving device comprising an inflatable member made of yielding flexible material, a vessel containing air or other gas under pressure, said vessel having an opening through which said air or gas may be discharged, said member having a portion overlying said vessel and having an opening therein aligned with said opening, means for engaging said portion and closing said openings, a member under tension holding said means in position and a member of material readily soluble in water holding said last mentioned member in holding position.

It is more specifically an object of the invention to provide a life-saving device comprising an inflatable member of yielding flexible material, a vessel containing air or other gas under pressure and having an opening therein through which said air or gas may be discharged, said member having a portion engaging said vessel with an opening therein aligned with said opening, said member having a portion folded to overlie said first mentioned portion and opening and carrying means engaging said first mentioned portion and covering said opening, a lever engaging said folded portion for holding said means in position, and a member of material readily soluble in water engaging said lever and holding the same in position.

These and other objects and advantages of the invention will be fully set forth in the following description made in connection with the accompanying drawings in which like reference characters refer to similar parts throughout the several views and in which:

Fig. 1 is a perspective view of a life-saving device embodying the present invention;

Fig. 2 is a view partly in side elevation and partly in vertical section of a portion of said device;

Fig. 3 is a vertical section taken on line 3—3 of Fig. 2;

Fig. 4 is a vertical section taken on line 4—4

2

of Fig. 2, said sections being taken as indicated by the arrows; and

Fig. 5 is a partial view similar to Fig. 2 showing the parts in different position.

Referring to the drawings, a device is shown comprising an inflatable member 10. While this member might be variously formed, in the embodiment of the invention illustrated it is shown as a substantially annular tube. Said tube 10 has a strap 11 connected to one end having spaced holes therethrough, said straps being adapted to cooperate with a buckle 12 carried on a strap 13 secured to the other end of said tube. Said member 10 is preferably made of yielding flexible sheet material. A vessel 15 is provided, and while this might take various forms, in the embodiment of the invention illustrated it is shown as of common bottle or cartridge form, the same having a neck portion 15a of reduced diameter which may be provided with a suitable closure 16. Vessel 15 is adapted to contain air or other gas under pressure and will commonly be charged with said gas through the neck portion 15a. Member 15 is provided with an opening 15b through the wall thereof and member 10 has a portion 10a overlying and engaging the outer side of vessel 15, said portion having an opening 10b therethrough aligned with opening 15b. A piece or disk 17 of yielding material of rubber or rubber-like composition is disposed to overlie portion 10a and opening 10b and will be secured to a portion 10c of member 10 which is folded to overlie portion 10a. A member 19 is provided and will be held under tension. In the embodiment of the invention illustrated, member 19 is in the form of a lever and has secured to one end thereof a piece or disk 20 of yielding material. Piece 20 is aligned with piece 17 and acts to hold the latter in engagement with portion 10a so that openings 10b and 15b are closed. Lever 19 is fulcrumed upon a small bracket 21 secured in any suitable manner to vessel 15, the same having a portion 21a having a convex surface engaged by lever 19. Lever 19 is held in the position shown in Fig. 2 by a member 22 which will be made of material which will be readily and very quickly soluble in water. Such material could be salt, sugar or one of a great many more materials which are readily and quickly soluble which can be made in solid form. Member 22 engages the other end of lever 19 and in the embodiment of the invention illustrated is shown as engaging the neck portion 15a.

In operation the member 10 will be worn on the body of the user. Should the user be thrown

into the water, as by falling from a boat or other place, the member 22 would be wetted and would immediately dissolve, thus releasing lever 19. The lever 19 would then not be supported at the end carrying member 22 and the pressure of the air or gas in vessel 15 would push member 11, portion 10c and member 20 away from portion 10a, as shown in Fig. 5. Portion 10a will preferably be connected to container 15. The air or gas from vessel 15 is now discharged into member 10 and the same will be inflated. The user will thus be supported in the water and can reach a place of safety.

From the above description it will be seen that I have provided a very simple and yet highly efficient automatically acting life-saving device. The member 10 may be made in various forms so as to be disposed under the clothing of the wearer, around the neck or around the waist. Sufficient air or gas is contained in the vessel 15 to effectively inflate member 10. It is obvious that the device will have a high degree of utility for the purpose intended.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A life-saving device having in combination, an inflatable member of flexible yielding material, a vessel containing gas under pressure and having an opening through which said gas may be discharged, said member having an opening therein in alignment with said opening and engaging said vessel, a second member covering said opening, a third member under tension holding said second member in position, and a member of material readily soluble in water holding said third member in position.

2. A life-saving device having in combination, an inflatable member of flexible yielding material, a vessel containing gas under pressure and having an opening through which said gas may be discharged, said member having an opening therein in alignment with said opening and engaging said vessel, a second member covering said opening, a lever engaging said second member, and a third member of material readily soluble in water holding said lever in holding position.

3. The structure set forth in claim 2, a bracket on said vessel on which said lever is fulcrumed, said third member of material readily soluble in water engaging one end of said lever for holding said second member in position.

4. A life-saving device having in combination, an inflatable member of flexible yielding material, a vessel containing air under pressure and hav-

ing an opening therein, a portion of said inflatable member having an opening therein aligned with said opening, said inflatable member being folded to have a portion overlying said openings, means on said last mentioned portions closing said openings and a member under tension holding said folded portion and means over said opening and a member of material readily soluble in water holding said last mentioned member in position.

5. A life-saving device having in combination, an inflatable member of flexible yielding material, a vessel containing air under pressure and having an opening therein, a portion of said inflatable member having an opening therein aligned with said opening, said portion being secured to said vessel, said inflatable member being folded to have a portion overlying said openings, a disk of yielding material secured to said last mentioned portion and engaging and covering said opening in said inflatable member, a lever having one end engaging said folded portion and a member of material readily soluble in water holding said lever in position.

6. The structure set forth in claim 5, said lever having a disk of yielding material thereon overlying said folded portion of said inflatable member in alignment with said opening.

7. A life-saving device having in combination, an inflatable member of flexible yielding material, a vessel containing air under pressure and having an opening through which said air may be discharged, said inflatable member having a portion overlying said vessel and having an opening therein aligned with said opening, said portion being secured to said vessel, said inflatable member having a folded portion overlying said first mentioned portion and opening, a piece of yielding material secured to said folded portion and engaging said first mentioned portion and covering said opening, a member under tension engaging said folded portion to hold the same and said piece in position, and a member of material readily soluble in water holding said last mentioned member in position.

8. The structure set forth in claim 7, said member under tension constituting a lever of the first class, a bracket secured to said vessel on which said lever is fulcrumed and said last mentioned member of soluble material engaging one end of said lever.
